UNITED STATES PATENT OFFICE.

FRANK OLKOWSKI, OF THREE LAKES, WISCONSIN.

MECHANICAL TOY.

1,393,638.

Specification of Letters Patent.

Patented Oct. 11, 1921.

Application filed February 10, 1921. Serial No. 443,910.

To all whom it may concern:

Be it known that I, FRANK OLKOWSKI, a citizen of Poland, residing at Three Lakes, in the county of Oneida and State of Wisconsin, have invented certain new and useful Improvements in Mechanical Toys, of which the following is a specification.

This invention relates to certain new and useful improvements in mechanical toys and 10 has particular reference to a toy of the figure type wherein a plurality of shiftable toy figures are adapted to be moved by a spring motor mechanism that is manually controlled.

15 The invention has particular reference to a toy embodying a casing with mechanism within the casing for supporting and moving a plurality of toy figures, preferably of the design of chickens over the upper surface 20 of the casing to cause the figures to be moved toward and away from a feeding receptacle supported on the casing.

With the above and other objects in view, the present invention consists in the novel 25 form, combination and arrangement of parts hereinafter more fully described and shown in the accompanying drawings and in which like reference characters indicate similar parts throughout the several views.

30 In the drawings,

Figure 1 is a top plan view of a toy constructed in accordance with the present invention, with the cover of the case removed,

Fig. 2 is a longitudinal sectional view 35 taken on line II—II of Fig. 1,

Fig. 3 is a cross sectional view taken on line III—III of Fig. 1 showing the connection between the spring motor and one of the sliding frames,

40 Figs. 4 and 5 are perspective views of the figure supporting slides,

Fig. 6 is a detail sectional view taken on line VI—VI of Fig. 3 showing the connection between the toy figure, the shifting slide 45 and the bar for supporting the connection, and

Fig. 7 is a detail sectional view taken on line VII—VII of Fig. 3 showing the pin connection between the coöperating slides for 50 shifting the toy figures.

Referring more in detail to the accompanying drawings, there is illustrated a mechanical toy embodying a casing containing spring motor mechanism and coöperating 55 slides with toy figures carried by the slides and extending above the casing, the figures

being caused to move in a swinging path from the opposite sides of the casing to the center thereof. The figures are constructed in simulation of chickens and a feed receptacle or pan is disposed centrally of the casing cover with the chickens moving toward and away from the feed pan. The casing embodies a bottom wall 1, end walls 2 and side walls 3 while a cover 4 is suitably secured to the upper edges of the side and end walls and is provided with longitudinal slotted openings 5 and transverse slotted openings 6 through which the supporting members for the toy figures extend.

Crossed supporting bars 7 and 8 are secured at their opposite ends to the side and end walls of the casing as shown in Figs. 1 to 3 and are spaced from the cover wall 4.

The shifting mechanism for supporting 75 the toy figures embodies a shiftable bar 9 slidably mounted on the supporting bar 8 with a block enlargement 10 at each end thereof provided with a transverse opening 11 into which inwardly directed lugs 12 of a 80 wire frame 13 are pivotally received, the lower ends of the wire frame 13 having inwardly directed fingers 14 pivotally received in the opening 15 in the supporting bar 8 as clearly shown in Figs. 2, 3, and 6. A 85 slide plate 16 is positioned above the sliding bar 9 and is movable in a direction at right angles to the sliding movement of the bar 9, the plate 16 carrying end extensions 17 having transverse openings 18 in the ends thereof. A wire frame 13 has the lugs 17 pivotally received in the end openings 18 and the lower end fingers pivotally received in openings 19 in the supporting bar 7 as shown in Fig. 2. The connection between the slide 90 bar 9 and slide plate 16 includes a pin 20 extending perpendicularly from the center of the slide bar 9 and projecting into the diagonal slot 21 in the slide plate 16.

The mechanism for shifting the slide plate 100 embodies a spring motor casing 22 secured to one side wall 3 of the casing and containing a spring motor placed under tension by the key 23 with the power shaft 24 projecting from the casing 2 and carrying a disk 25 105 upon the inner end thereof with an eccentric pin 26 connected by a pitman 27 to one side of the slide 16, as at 28. The spring motor mechanism includes a toothed wheel 29 with which a finger 30 of a stop lever 31 110 is adapted to engage for arresting movement of the spring motor.

To place the spring motor under tension, the finger 30 of the stop lever is disengaged from the wheel 29 and the key 23 rotated in the desired direction. The rotation of the 5 shaft 24 will communicate reciprocatory sliding movements to the sliding plate 16 by the pitman connection 27 between the plate and the shaft. The slide 16 extending at right angles to the slide bar 9 will communicate a sliding movement to the bar 9 by the 10 diagonal slot 21 in the plate 16 receiving the pin 20 of the slide bar as will be obvious. The upper ends of the wire frames 13 have secured thereto toy figures in the form of 15 chickens indicated by the reference numeral 32 while a feed pan 33 is positioned on the casing cover 4, to cause the figure toys 32 to move in directions toward and away from the feed pan. The operation of the device 20 is under the control of the stop lever 31 and at will, the figure 30 of the stop lever is moved into engagement with the wheel 29 of the spring motor to arrest movement thereof. The slide plate 16 and slide bar 9 are 25 maintained in their correct positions by the wire frames 13 pivoted to the supporting bars 7 and 8 and inclosing the sliding members, thus causing the toy figures to ascribe a direct line of travel in moving toward and 30 away from the feed pan 33. Considerable amusement may be obtained from the operation of this device and the speed of travel of the figure toys may be readily controlled by the winding of the spring motor mechanism 35 while the operation of the device is controlled by the stop lever 31.

While there is herein shown and described the preferred embodiment of the invention, it is nevertheless to be understood that minor changes may be made therein without departing from the spirit and scope of the invention as hereinafter claimed. 40

What is claimed as new is:

1. A mechanical toy comprising a casing, 45 fixed supports within the casing, a pair of crossed sliding members within the casing moving in directions at right angles to each other, figure toys including supporting frames pivoted to the fixed supports and the sliding members, a spring motor mechanism, 50 a pitman connection between the motor mechanism and one of said slides and a pin and slot connection between the slides. 55

2. A mechanical toy comprising a casing, 55 fixed supports within the casing, a pair of crossed sliding members within the casing moving in directions at right angles to each other, figure toys including supporting frames pivoted to the fixed supports and the sliding members, a spring motor mechanism, 60 a pitman connection between the motor mechanism and one of said slides, a pin and slot connection between the slides and means for arresting movement of the spring motor mechanism. 65

In testimony whereof I affix my signature in presence of two witnesses.

FRANK OLKOWSKI.
